Application filed January 14, 1885. Term of patent 3½ years.

To all whom it may concern:

Be it known that I, JAMES L. FOLSOM, of Brooklyn, New York, have invented a new and original Design for Carpets, of which the following is a specification, reference being had to the accompanying photograph, which forms a part of the same.

The invention relates to a design to be worked into or upon surfaces such as carpets or similar fabrics; and it consists in the novel configuration and grouping of figures herein specifically shown and claimed.

The accompanying photograph is a face view of a carpet showing my new design.

The design consists of separate diamond-shaped groups of small flower and leaf figures arranged symmetrically, some with and some without stems, and placed closely together and filling evenly the entire face of the design, all as clearly shown in the photograph. 15
